UNITED STATES PATENT OFFICE.

HENRY FRAPPART AND JEAN BAPTISTE BOUVIER, OF KINCAID, ILLINOIS.

RAIL-CLAMP.

1,353,577.

Specification of Letters Patent. Patented Sept. 21, 1920.

Application filed March 23, 1920. Serial No. 367,989.

To all whom it may concern:

Be it known that we, HENRY FRAPPART and JEAN BAPTISTE BOUVIER, a citizen of the United States, and a subject of the King 5 of Belgium, respectively, residing at Kincaid, in the county of Christian and State of Illinois, have invented certain new and useful Improvements in Rail-Clamps, of which the following is a specification.

10 This invention relates to rail clamps, and particularly to a device of this character intended for use in mines and in other like connections, to hold rails in place.

An object is to provide a clamp structure 15 by which a tread rail is held in an upright relation and a bed rail or a length of rail laid to fit within the tread rail is clamped and held thereagainst to secure the tread rail in place and to present a portion of the 20 bed rail parallel with and adjacent the head of the tread rail to guard against and prevent derailment of cars traveling thereon.

A further object is to so construct the various portions of the clamp that the bed rail 25 is wedged and is positively held against springing or otherwise moving from its interfitted position with relation to the tread rail.

Yet another object resides in constructing 30 and arranging the parts in such manner that the clamp can be moved along the rails or either or both rails can be slid endwise therein previous to tightening of the clamping portions to thus obtain a proper fitting of 35 the parts, and in so making these clamping portions that they are releasable for fitting and readjustment in new positions of use.

With these and other objects in view 40 which will be apparent from the specification, drawings, and claims, this invention includes certain novel features of construction and combinations of parts which will now be set forth.

In the drawings:

45 Figure 1 is a transverse vertical sectional view taken through a tread rail and a bed rail having our improved rail clamp applied thereto.

Fig. 2 is a fragmentary top plan view 50 showing the parts illustrated in Fig. 1.

Fig. 3 is a perspective view of the clamp member of the structure.

In the present disclosure we have illustrated the tread rail 1 and the bed rail 2 as 55 being of substantially standard design and of the T-rail type, although as the descrip-

tion progresses it will be appreciated that this invention might be employed in conjunction with and be used for securement of other types of rails.

The rail clamp consists in the main of a clamp member 3 of wrought steel or other material possessing the requisite strength. This clamp member is made up to include a flat body portion 4, at one end of which a 60 base flange receiving hook 5 is formed, the remaining end being provided with an upstanding wedge receiving portion 6. This wedge receiving portion is inclined slightly 65 from a vertical relation toward the hook 5, and at its upper end is shaped in a hook 70 formation 7 overhanging the body portion 4 and substantially parallel therewith. The inner side of the upstanding portion 6 is faced to form a bearing surface and is preferably tapered or inclined from side to side 75 as indicated by the dotted lines 8, in Fig. 2.

The base flange receiving hook 5 is shaped to conform substantially to one side of the base flange of a rail, when the rail is placed 80 in an upright relation on the body portion 4, substantially as rail 1 is fitted in Fig. 1. The head of a standard rail is of such form and size that when turned, as is rail 2 in Fig. 1, it will fit within and substantially 85 fill the space at one side of the web of the upright or tread rail and will bear between the base flange and the rail head, and the body portion 4 of the clamp member 3 is of sufficient length that the upright extension 6 90 with the hook portion 7 thereof are entirely clear of the bed rail 2. The incline of this upstanding portion 6 is gaged to bring the bearing face thereof substantially parallel 95 with the adjacent face of the base flange of bed rail 2.

A clamp wedge 9, of quadrangular shape in cross section is tapered on its outer face 10 to a degree corresponding with the taper of the bearing face of extension 6. Opposite sides of wedge 9 are shaped to fit the upper and lower faces of body portion 4 and hook 7 respectively, and the remaining sides of the wedge are shaped to conform to the angularly disposed base flange of bed 105 rail 2 and the bearing surface of upright extension 6.

In the use of our improved rail clamp tread rail 1 is fitted in place on the body portion 4 of clamp member 3 beneath hook 110 5, if the clamp member be supported, or the clamp member is thus fitted to a rail which

has been laid in place. Bed rail 2 is then dropped into place or is slid endwise to be embraced within the confines of clamp member 3 with the head thereof bearing against tread rail 1. Clamp wedge 9 is then inserted and driven into place, this wedge clamping bed rail 2 securely against tread rail 1 and forcing the base flange of this latter rail to be caught firmly within the hook portion 5.

10 By reason of the inclined disposition of upright extension 6 and the corresponding formation of wedge 9, clamping force is exerted upon bed rail 2 to retain the same in the inclined relation as shown and to cause 15 a positive clamping force to be exercised upon tread rail 1 directly forcing the same into the grip of hook 5 and down against body portion 4. This peculiar formation of wedge 9 and the parts adjacent thereto 20 brings about a co-active result by which the tread rail is securely clamped and retained in place and both rails are held against turning movement or displacement within the clamp. It has been found that 25 in the use of this rail clamp in mines and other like connections full length rails may be fitted in place as bed rails until a shaft has been extended sufficiently that there is room in front to permit it to be secured in 30 place as a tread rail, and in this fitting bed rail 2 acts not alone to hold tread rail 1 in place, but also the base flange thereof is presented adjacent and parallel with tread rail 1 to prevent derailment of cars traveling on 35 said rail.

While in the foregoing we have shown and described only one specific embodiment, and have only briefly alluded to other forms and constructions which might be used, it 40 will be apparent that several changes might be embodied, and may even become necessary under varying conditions of use, in view of which we wish to be limited only to such points as are covered by the claims.

45 We claim:

1. A rail clamp including a clamp member having a hook formation at one end to engage with the base flange of a tread rail and provided with an upright extension at 50 its remaining end, the body of said clamp

member being made sufficiently long to accommodate a bed rail placed with the head thereof between the head and base flange of the tread rail, and a wedge to be driven between the upright extension and the base flange of the bed rail.

2. A rail clamp including a clamp member shaped at one end to receive an upright tread rail and made of sufficient length to accommodate a bed rail placed on one side 60 with the head thereof between the base flange and head of the tread rail, said clamp member having an upright extension on its remaining end spaced to clear the base flange of the bed rail and inclined to be substantially parallel therewith, and a clamping wedge to be inserted between said upright extension and the base flange of the bed rail and having the bearing faces thereof angularly disposed to follow the incline 65 of said extension and flange.

3. A rail clamp including a clamp member consisting of an elongated body portion having a hook formation at one end to receive the base flange of an upright tread rail 75 placed on said body portion, said body portion being of sufficient length to receive the base flange of a bed rail placed on its side parallel to and with its head received between the base flange and head of the tread rail and being provided with an upright extension on its remaining end angularly disposed to follow the incline of the base flange of the bed rail, said upright extension being faced on that side adjacent the bed 80 rail to provide an inclined bearing surface and having a hook at its upper end overhanging said bearing surface and extending substantially parallel with said body, and a tapered wedge made of a width to fit between said overhanging hook and the body portion of the clamp member and having its side faces inclined with respect to the wedge faces to follow the incline of the base flange 85 of the bed rail and the upright extension. 95

In testimony whereof we affix our signatures,

HENRY FRAPPART.
JEAN BAPTISTE BOUVIER.
